OF NEW YORK, N. Y., A CORPORATION OF NEW JERSEY.

PROCESS OF CANNING.

1,306,813.

Specification of Letters Patent. Patented June 17, 1919.

Application filed October 27, 1913. Serial No. 797,537.

To all whom it may concern:

Be it known that I, JOHN G. HODGSON, a citizen of the United States, residing in Maywood, in the county of Cook and State of Illinois, have invented a new and useful Improvement in Processes of Canning, of which the following is a specification.

This invention relates to improvement in process of canning and more particularly to 10 the process of canning or preserving fruits, vegetables, syrups and other food products in what are commonly termed "friction top" cans.

As is well known, the general method of 15 canning or preserving food products is accomplished by first placing the food products in a can, then partially exhausting the air from the can, either by placing the can in a vacuum chamber or by attenuating the 20 air by means of heat, and finally sealing the contents while the can is thus partially exhausted or the air therein in an attenuated condition. Hitherto, so far as I am aware, friction top cans have never been used, in 25 the carrying out of this process on account of the fact that it has generally been considered impossible to obtain an absolutely hermetic or perfectly air tight joint with the use of friction seals, the use of friction 30 top cans having been limited generally to transporting paints, powders and the like, which do not have to be processed or cooked and which are not permanently injured by contact with air. Solder cans employing a 35 cap hole or stud hole, which were the first type of cans used in canning or processing food products, have gradually been supplanted by what are termed the "sanitary" or open top can in which the final closure 40 or cover is double seamed to the can body. Several difficulties have been encountered in 45 processing food products in the sanitary cans, among which may be mentioned: exposure of the contents during the heating step when the cover is off the can which causes scorching of the food products; danger of spilling while the cans are being passed through the exhaust box used for 50 heating the contents; and danger of some of the contents getting on or between the seam forming flanges and thus preventing a perfect joint between the cover and can body when the latter are seamed. I am aware, however, that recently some of these difficulties 55 encountered with the use of sanitary

cans have been overcome by clenching, snapping or otherwise securing the cover to the can body in such a way as to permit the escape of the expanded gases before the can is passed through the exhaust box or steam 60 cooker, after which the cover and can body are tightly double seamed to seal the can.

With a double seamed can, however, it is not always possible to determine whether or not the joint formed is a perfect one and 65 even when the double seam joints are thought to be perfect, actual tests have proven that if the cans are kept for several years before being used, as often happens in the case of exploring parties and places 70 far removed from ordinary transportation, air will gradually enter the can through the double seams and thus cause deterioration of the food. From the preceding, it will be seen that the container which will keep food 75 products indefinitely must be sealed either by all metal joints or solder seams such as with the old type of solder can or with hermetic gasket seals. Solder cans, as before pointed out, are gradually being discontinued owing to several disadvantages incident to their use. If cans or containers employing a hermetic gasket seal are used, it is necessary that the process be so arranged that the cans after being filled may be processed 80 by passing through the exhaust box without danger of spilling the contents or of scorching or burning the contents and the final sealing accomplished at such a time and in such a manner that the partial vacuum 85 within the can will itself practically cause the formation of the hermetic gasket seam. 90

The object of my invention is to devise a process of canning wherein friction top cans employing a gasket hermetic seam may be 95 advantageously employed, at the same time insuring a perfect, absolutely air-tight joint.

The invention furthermore consists in the novel steps and combinations of novel steps as herein shown, described or claimed.

In the drawing forming a part of this specification, Figure 1 illustrates suitable mechanism for carrying out my improved process and Figs. 2, 3 and 4 are sectional views of a container adapted for carrying out my process and showing respectively the can as it is first filled, the can with the cap loosely applied thereto as it enters the exhaust box and while the contents of the can are being heated and the can as it is finally 110

closed by means of a friction cover pressed down against the cap to form the hermetic gasket seal between the cap and can top.

In said drawing the body of the can or other container which may be of metal or other suitable material, is designated by the reference 10, the same having a bottom 11 and a top 12 secured thereto. The top 12 is provided with a countersunk central portion having an opening 13 therein surrounded by a horizontally disposed shelf or ledge 14 on which is placed a gasket of rubber or other suitable material 15. The vertical wall 16 of the countersunk portion of the cover 15 forms a friction seat coöperable with the friction seat wall 17 of a countersunk cover 18.

In carrying out my process, the cans will first be filled, as shown in Fig. 2, after which an annular cap 19 will be placed loosely within the countersunk portion of the can top on top of the gasket 15. The cap 19 is provided with an inturned edge 20 spaced from the main, slightly downwardly caved portion 21 thereof. After the cap is placed in position, as shown in Fig. 3, the air within the can is attenuated and the contents heated by passing the can through an exhaust box 22 heated by a coil of steam pipe 23, the cans being conveyed through the exhaust box as by means of an endless conveyor 24 of any well known construction, the exhaust box being provided with flap doors 25 at each end to better retain the heat therein. As will be apparent, during the passage of the filled cans through the exhaust box, the heated and expanded gases escape freely through the loose joint between the cap 19 and the gasket 15 and yet at the same time, the contents are fully protected from injury and there is practically no danger of spilling or escape of the can's contents. While the air within the can is in the attenuated condition thus created by the heat, a friction cover is placed in proper position and is then forced home by a plunger 26 beneath which the cans may be conveyed after leaving the exhaust box. In actual practice, the partial vacuum created within the can after the can cools will be sufficient in itself to draw the cap firmly down against the gasket on the can top and the friction cover will automatically augment this pressure after it is pressed home on account of the inturned edge 20 of the cap which forms a yieldable compression device between the friction cover and the cap. The friction cover also provides an additional, friction seal which supplements the hermetic gasket seal.

Although I have herein described my process as carried out by apparatus employing an exhaust box or steam cooker, yet it

will be obvious to those skilled in the art that the attenuated condition of the air 65 within the can before the friction cover is applied, may be obtained by placing the filled can within a vacuum chamber and then applying the friction cover before the can is subjected to normal or atmospheric pressure. 70 It is also apparent that the hermetic seal formed between the cap, gasket and can top will in itself generally be all that is necessary to hermetically seal the can, and that instead of employing a true friction cover, 75 which of course provides a friction seal as above indicated, any sort of a frictionally held cap-retaining member may be used, the function of the cap retaining member being to prevent accidental removal or dislodgment of the cap after the hermetic seal has been formed. Such a cap retaining member might, for instance, be in the form of an annular member similar to the friction top with its central portion cut-out. 80

In opening the can, the friction cover or friction cap-retaining member will first be removed in the usual manner, after which the cap will be punctured by some sharp instrument in order to equalize the pressure on 90 both sides of the cap, whereupon the latter may be easily pulled off.

I claim:—

1. The herein described process of cooking and sealing the contents of cans, which consists in filling the can with the contents to be processed or cooked, heating and cooking the contents, sealing the can by a gasket and superposed closure, and maintaining a metallic spring pressure on said gasket irrespective of any shrinking or setting of the same. 95

2. The process of canning which consists in: filling a can having an open top; applying a gasket and superposed metallic spring 100 closing cap loosely to the top of the can to cover the opening of the can so as to admit of the escape of air; processing the filled can by heat and attenuating the air within the can; admitting atmospheric pressure to the exterior of the can and causing such pressure as the can cools to hold the said loose cap tightly in place so as to close the can against the entrance of air; and, while there is thus maintained more or less of a vacuum 110 within the can, applying pressure upon the said loose spring cap, and maintaining the spring pressure of the latter on the gasket. 115

In witness whereof, I have hereunto set my hand this 22nd day of October, 1913, in the presence of two subscribing witnesses.

JOHN G. HODGSON.
